(57) **CLAIM**

The ornamental design of an artificial fishing lure, as shown and described.

DESCRIPTION

FIG. 1 is a front elevation view of an artificial fishing lure showing my new design;

FIG. 2 is a bottom plan view thereof;

FIG. 3 is a top plan view thereof;

FIG. 4 is a right side elevation view thereof; and,

FIG. 5 is a left side elevation view thereof.

The broken line showing of environment in the drawings is for illustrative purposes only and forms no part of the claimed design.
